UNITED STATES PATENT OFFICE

STUART BALLANTINE, OF WHITE HAVEN, PENNSYLVANIA, ASSIGNOR TO BOONTON RESEARCH CORPORATION, OF BOONTON, NEW JERSEY, A CORPORATION OF NEW JERSEY

AUDION CIRCUIT

Application filed November 3, 1926. Serial No. 146,038.

This invention relates to an electrical circuit for use in association with audion tubes, and especially to such a circuit providing means for reducing or preventing reaction between the output circuit of an audion stage and the input circuit thereof. It is applicable to audion stages in general, including audion amplifier stages suitable for use in radio receiving sets, or in radio or intermediate frequency amplifiers whether or not embodied in a radio receiving set.

In my copending application, Serial No. 629,702, filed April 3, 1923, I have heretofore disclosed and claimed an electrical circuit for use in association with audion tubes and providing means for accomplishing this and other desirable results. This is done by arranging the impedance mesh of an audion stage in the form of an alternating current Wheatstone's bridge of which the input circuit of the audion stage forms one conjugate arm and the output circuit of the audion stage forms the other conjugate arm. That application relates particularly to a class of alternating current bridge circuits having a balancing arm of the bridge mesh between grid and plate of the audion tube and constituting a substantially pure capacity. My present invention relates to a class of bridge circuits having a balancing arm between grid and plate of the audion tube and comprising an inductance.

I have found that by arranging the impedance mesh of an audion stage in the form of an alternating current Wheatstone's bridge of which the input, or isolated, circuit of the audion stage forms one conjugate arm, the output, or plate-filament, circuit of the audion stage forms the other conjugate arm, and one balancing arm comprises inductance between grid and plate of the audion tube, I obtain an audion stage of which the output circuit may be electrically isolated from the input circuit in such a way that there is substantially no reaction between them. By appropriately balancing the bridge mesh such reaction may be diminished to the desired degree. The audion stage thus approaches a unidirectional repeater. Any desired number of such stages may be cascaded together

without reacting one upon the other, and in the case of amplifier stages the amplification obtained from the cascaded stages increases in substantially geometrical progression.

Fig. 1 represents diagrammatically a general case of a Wheatstone's bridge mesh associated with an audion tube. The output circuit of the audion stage is between the plate and filament of the audion tube and forms one conjugate arm of the bridge. The input circuit of the audion stage is not between grid and filament of the tube but is between the grid of the tube and an intermediate point, 2, in the output or plate-filament circuit. The input circuit of the stage therefore forms the other conjugate arm of the bridge, and when the bridge mesh is balanced the input circuit of the audion stage is electrically isolated from the output circuit thereof. I may therefore designate the input circuit of the stage as the "isolated" circuit, since it is by virtue of the electrical isolation of this input circuit from the output circuit that reaction from one to the other is prevented.

In Figs. 2a and 2b I have diagrammatically shown two circuits each embodying my invention. That is, in each case the impedance mesh of the audion stage is arranged as a Wheatstone's bridge having four balancing arms and two electrically isolated conjugate arms, and the balancing arm between grid and plate of the audion tube comprises the inductance L_m . In physical embodiments of the circuit this inductance is effectively shunted by the distributed capacity of the coil and by the inherent grid-plate capacity of the audion tube, but I prefer to use a coil of such size that the reactance of this balancing arm is inductive for frequencies at which the circuit is intended to operate.

The principles of electrically balancing an alternating current bridge mesh are of course familiar to those skilled in this art. In general they require the use of another inductive balancing arm adjacent L_m , and further require that the remaining two balancing arms comprise impedances of a character (inductive, capacitive, or resistive) similar to one another, although they may be of the same or different character from that of the arm L_m .

An exception, however, occurs in the circuit of Figs. 11a and 11b, which is discussed below.

The arm L_m having already been determined, there are two positions in which the adjacent inductive arm may be placed. In Fig. 2a it is shown at L_1 and in Fig. 2b at L_c .

In Fig. 2a there remain two balancing impedances Z_c and Z_2 as yet undetermined. These must be similar in character in order to give a balance, but they may be either capacitive, resistive, or inductive. These three alternatives are shown in Figs. 3a, 3b, and 3c, respectively. As already pointed out above, the inductance L_m is shunted by the internal grid-plate tube capacity C_m , in addition to any distributed coil capacity which may be present. In order to secure a balance independent of frequency it may therefore be desirable to shunt the adjacent inductive arm by a capacity of proper order. This is indicated at C_m and C_1 , in Fig. 3a, but to simplify the diagrams it has been omitted from the other figures.

The alternative shown in Fig. 3a has a particular advantage, that regeneration may take place in the audion tube while the input and output circuits of the audion stage are maintained isolated from one another by the bridge mesh. This is applicable either to an oscillator or to an amplifier, and in the latter case a high amplification is obtained from each stage, while any number of regenerative amplifier stages may be cascaded without acting upon each other. This has not heretofore been possible.

The arrangement of Fig. 2b leaves two undetermined impedances Z_1 and Z_2 , which must fulfill the requirements already stated. They may therefore be both capacitive, both resistive, or both inductive. The first two alternatives are shown in Figs. 4a and 4b respectively. The third alternative gives the same circuit as Fig. 3c and is therefore not shown.

In order to obtain a bridge balance independent of frequency it is necessary either that the ratio of the two impedances forming each pair of balancing arms be invariant of frequency, or that each pair of impedances be so selected that their ratios vary with frequency in the same manner. In some cases it is advantageous to couple either the input circuit or the output circuit of the stage to two adjacent balancing arms of the bridge by means of mutual inductance. The balancing arms then become composite because of the mutual inductance, but a balance may be maintained by virtue of the above principle. In Fig. 5a the input or isolated circuit is inductively coupled to the arms L_c and L_2 , which thus become composite. In Fig. 5b the output circuit is inductively coupled to the arms L_1 and L_2 in a similar manner. I have

found that arrangements of this sort are well adapted to use in commercial amplifiers.

Fig. 6a illustrates a particular application of my invention, making use of inductive coupling to obtain proper direct current paths. This is the circuit of Fig. 3a used as one stage of a tuned radio frequency amplifier. The isolated or input circuit comprises the tuned transformer T_1 . The output circuit includes the tuned transformer T_2 . This transformer has two primary windings P_1 and P_2 which may be closely associated so that the coupling approximates unity. A double winding is suitable and may act electrically as a single coil, the impedance between adjacent terminals being vanishingly small. In this case the two primary windings serve to supply the grid and plate electrodes with their proper operating direct current potentials by means of the batteries "B" and "C".

Fig. 6b illustrates another method of arranging the direct current battery paths. Here the direct current plate potential is kept off the grid by the insulating condenser C^1 . The proper grid bias is obtained by means of the resistance R_e and the battery "C". This forms an arm of composite impedance which may be balanced if necessary by connecting another resistance R_2 across the adjacent capacitative arm C_2 as shown.

Fig. 7a shows the employment of inductive coupling in the balancing arms of the circuit of Fig. 3c. The windings P_1 and P_2 are closely coupled and constitute the primary of the output transformer of which the secondary is denoted by S . The inductive coupling serves to keep the direct current plate potential of the battery "B" from the grid. The proper grid bias is obtained by the battery "C". This type of amplifier stage is well adapted to cascade arrangements in which the filament junctions of the several bridge meshes are common.

Fig. 7b shows another arrangement of the "A" and "B" batteries, adapted to cascaded systems in which the intermediate points "2" of the successive bridge meshes are common. The filament circuit is completed through the portions P_1' and P_2' of the closely coupled primary windings. Unity coupling between the two primary windings P_1 and P_2 may be desirable but is not vital.

In cascading a plurality of these stages I may make any one of the four corners of the bridge mesh common to the several stages and ground this common point, if I so desire. In commercial apparatus terminals F and 2 are perhaps most convenient for this purpose, and Figs. 7a and 7b show suitable battery arrangements applied to the circuit of Fig. 3c.

Figs. 8a and 8b show battery arrangements suitable for use in cascaded systems having

common plate terminals. These diagrams are also based upon the circuit of Fig. 3c. In Fig. 8a the filament circuit is completed around the direct current path furnished by the four coils which constitute the bridge arms; in Fig. 8b it is completed by means of the coil L which may or may not be coupled to the coils L1 and L2 of the balancing arms. In Fig. 8a a by-pass condenser is shown in parallel with the filament as a means of eliminating the filament impedance from the bridge. This may not be necessary in all cases.

Fig. 9 shows a section of a cascaded tuned transformer-coupled amplifier compounded of stages of the type shown in Fig. 6a. A description of this stage has already been given so that the diagram is largely self-explanatory. The filament terminals of the several bridge meshes are made common. The filaments are connected in parallel and are supplied by the "A" battery. The lines to the "B" battery and "C" biasing battery are also designated. Condensers C are by-pass condensers of low impedance, their function being to prevent coupling between stages due to common impedances in the batteries and wiring. Their effect may be increased by inserting choke coils in the lines between the by-pass condensers and the batteries. Various additional by-pass condensers and filters may be employed in systems comprising a large number of stages, as well as electrical shielding of the separate stages if desired. Commonly controlled variable tuning elements in the several stages may also be useful.

Instead of tuning the coupling transformers by means of the variable condensers shown, the condensers C_e and C₂ may be used for this purpose by connecting them together mechanically so that their variations of capacity take place in such a way as to preserve their impedances in the proper ratio.

Fig. 10 shows a single stage in which the coils L_m and L₁ are used as the secondary of a coupling transformer, the couplings being indicated by brackets. By properly coupling L_m and L₁ a low impedance between G and 2 may be obtained, while at the same time giving the desirable high impedance between the corner of the mesh at P and G or 2. For this coupling the sign of the mutual inductance should be such that between the terminals G and 2 the inductance of the two coils in series is L_m+L₁-2M.

Fig. 11a illustrates schematically another bridge circuit arranged according to my invention to give a balance independent of frequency with an inductive balancing arm between grid and plate of the audion tube. In this case two similar resistive arms are placed opposite one another instead of adjacent, and the inductance L_m is balanced by means of a capacity C₂ placed in the opposite

arm. The condition for balance is well known to be $Lm/C_2 = R_1 R_2$. Fig. 11b illustrates a detailed circuit including batteries, and using inductive coupling to insulate the grid from the direct current potential of the plate. 70

My invention is obviously not confined to an audion tube of the three-electrode type. It may extend to any vacuum tube stage having circuits which it is desired to isolate from one another. The application of my invention to four-electrode audion tubes of the type having two grid electrodes is shown in Figs. 12a and 12b. In the former, G₂ is used as control grid and G₁ is given a positive bias; in the latter G₁ is used as control grid and G₂ is given a positive bias. 75

In all of the above circuits coupling the coils of the balancing arms with one another and with coils in the conjugate arms is contemplated, and this may be carried out as already indicated or in a manner which will be apparent to one familiar with this art. Moreover my invention is not restricted to a completely balanced network but includes 80 the combination of an audion tube with a physical bridge structure as shown. 85

It is also understood that the invention is not limited to the specific circuits which I have described, since various changes or 90 modifications may be made in the circuits without departing from the spirit of my invention. 95

I claim:

1. An electrical amplifier stage comprising 100 an audion tube and an impedance network associated therewith and arranged in the form of an alternating current Wheatstone's bridge of which the input circuit of the audion stage forms one conjugate arm and the output circuit of the audion stage forms the other conjugate arm, said bridge having two adjacent balancing arms each comprising an inductance and effectively located respectively between grid and plate 105 of said tube and between the plate of said tube and an intermediate point of an alternating current plate-filament path thereof, and two adjacent balancing arms each having a capacitive reactance and located in the two remaining balancing-arm positions in 110 said bridge. 115

2. An electrical amplifier stage comprising 120 an audion tube and an impedance network associated therewith and arranged in the form of an alternating current Wheatstone's bridge of which the input circuit of the audion stage forms one conjugate arm and the output circuit of the audion stage forms the other conjugate arm, said bridge having a balancing arm comprising an inductance located between the grid of said tube and a point in said bridge mesh which 125 is electrically equivalent to, and associated 130

with, the plate of said tube by virtue of a closely coupled twin winding.

3. An electrical amplifier stage comprising an audion tube and an impedance network associated therewith and arranged in the form of an alternating current Wheatstone's bridge of which the input circuit of the audion stage forms one conjugate arm and the output circuit of the audion stage forms the other conjugate arm, said bridge having two balancing arms each comprising an inductance, one of said balancing arms being effectively located between grid and plate of said audion tube and the other of said balancing arms being effectively located adjacent thereto between the plate of said tube and an intermediate point in an alternating current path thereof, and capacitive impedance blocking the flow of direct current from said plate along either of said two balancing arms.

4. An audion amplifier stage comprising an audion tube having a grid, a plate and a cathode, two inductances serially connected between plate and cathode, an inductance effectively connected between grid and plate, an inductance between grid and cathode, an output circuit for said stage effectively connected across plate and cathode, and a tuning condenser connected between grid and the junction of said serially connected inductances, said inductances constituting the arms of a Wheatstone bridge which may be balanced to isolate said condenser and said output circuit.

5. In a radio frequency amplifier stage, in combination, an audion tube having a grid, a plate and a cathode, inductive impedance connecting said cathode and grid, impedance connecting said cathode and plate, an inductive impedance effectively connected between grid and plate, means preventing the direct current potential of said plate from reaching said grid, said impedances comprising the four balancing arms of a Wheatstone bridge network across which the input circuit and the output circuit of said stage are arranged as the conjugate arms thereof, whereby said bridge network may be balanced to suppress self-oscillation.

In testimony whereof, I affix my signature.
STUART BALLANTINE.
